UNITED STATES PATENT OFFICE.

CLARENCE C. STIRLING, OF HARTFORD, CONNECTICUT, ASSIGNOR TO
EDMUND HUDSON, OF TEMPLETON, MASSACHUSETTS.

ELECTRIC-ARC LAMP.

SPECIFICATION forming part of Letters Patent No. 593,697, dated November 16, 1897.

Application filed February 6, 1897. Serial No. 622,264. (No model.)

To all whom it may concern:

Be it known that I, CLARENCE C. STIRLING, of Hartford, county of Hartford, State of Connecticut, have invented an Improvement in Electric-Arc Lamps, of which the following description, in connection with the accompanying drawings, is a specification, like letters and figures on the drawings representing like parts.

10 This invention relates to electric-arc lamps of that class in which the rays of light therefrom are reflected upwardly and in which the arc is maintained in a fixed or predetermined position.

15 The invention has for its objects, first, to improve the construction of the carbon-feeding mechanism, whereby the carbons are automatically fed toward each other to maintain the arc in a fixed or predetermined position; second, to provide an improved form or construction of actuator for said carbon-feeding mechanism, and, third, to improve certain details in the general construction of the lamp.

The invention consists in embodying in an arc-lamp certain feeding mechanism for the carbons, comprising a hollow shaft and a rod which enters and moves telescopically therein, said hollow shaft being externally screw-threaded and receiving upon it the lower-30 carbon support, which rises and falls as said hollow screw-shaft is turned in one or the other direction, and said hollow screw-shaft being also internally screw-threaded and receiving within it the aforesaid rod, which is externally screw-threaded, and as said hollow screw-shaft is turned said rod will be moved up and down according to the direction of movement of said hollow screw-shaft, and the screw-threads are so arranged that 35 as said hollow screw-shaft is turned in one direction the lower-carbon support thereon will be raised and the screw-threaded rod will be lowered, and vice versa, and said rod is connected with the upper-carbon support, 40 and consequently said upper-carbon support will move with said rod. The pitch of the screw-threads vary, so that the carbons will move toward each other at different rates of speed, which is proportioned to the consumption of the respective carbons, so that the arc can be maintained in a fixed or predetermined position.

The invention also consists in an actuator for the carbon-feeding mechanism consisting of a motor, comprising a field-magnet which 55 is included in circuit in series with the carbons, and a rotary armature which is included in a normally open branch circuit, and a circuit-closer or switch is provided for said branch circuit, which is operated by a 60 device controlled by the field-magnet of the motor, which device is responsive to variations produced by the varying resistance of the arc—as, for instance, a supplemental armature may be provided for said field-magnet 65 which is connected with said switch or circuit-closer, and said supplemental armature has a retractor which is overcome by the attractive force of the field-magnet when but little resistance is produced by the arc, but 70 when said resistance is increased to a considerable extent said retractor will overcome the attractive force of said field-magnet, retracting the armature, and thereby causing the switch or circuit-closer to close said normally open branch circuit. 75

The rotary armature of the motor is connected with the carbon-feeding mechanism, and when the switch or circuit-closer of the branch circuit is open said rotary armature 80 will remain at rest, but when said switch or circuit-closer is operated and the branch circuit closed said rotary armature will revolve and operate the carbon-feeding mechanism.

Figure 1 is a side elevation of an electric-arc lamp embodying this invention. Fig. 2 is a front elevation of the same, parts thereof being broken away for clearness. Figs. 3 and 4 are details to be referred to, and Fig. 5 is a diagram of the electric circuit as arranged in my improved arc-lamp. 85 90

A and B represent, respectively, the lower and the upper carbons. The lower carbon is placed in a socket formed in a holder *a* and securely held in place by means of a thumb-screw 95 *a'*. The holder *a* is formed with a shank *a*², which projects down through a bushing *a*³ and a spiral spring *a*⁴ encircles said shank *a*², the lower end of which rests upon a shoulder formed in the bushing and the upper end 100 bears against said holder, and the action of said spring is to thrust the lower carbon-holder *a* upward. The bushing *a*³ is mounted in a similar bushing *a*⁵ of insulating ma-

- terial which is fixed in the center of a disk *b*. The disk *b* is mounted to slide vertically upon a guide post or bar *c*, and is formed with a depending sleeve *b'*, which embraces said post *c* and is insulated therefrom by means of a lining *b''* of any suitable insulating material. The disk *b* is also formed with a depending boss *b'''*, which is internally screw-threaded to engage the externally-screw-threaded shaft *d*, which latter is revolved in the manner and by the means to be hereinafter described, and acts as a feeding-screw to move vertically the disk *b* and lower carbon carried thereby. The post *c* is fixed at its lower extremity in a base *C*, in which base is also journaled the lower extremity of the feeding or screw shaft *d*. The screw-shaft *d* has mounted loosely thereon at or near its lower end a worm-gear *e*, upon which is mounted a pawl *d'*, that engages a ratchet-wheel *d''*, fixed to said screw-shaft *d*, and said worm-gear *e* is engaged by a worm *f*, fixed to a shaft *D*, which is herein shown as the shaft of the rotary armature of an electric motor. The shaft *D* is caused to rotate at certain times, as will be hereinafter described, and through the medium of said worm *f* and worm-gear *e* the screw-shaft *d* will be rotated in a direction to feed the disk *b* and parts borne by it upward a short distance and until said shaft *D* ceases to revolve. The upper carbon *B* is placed in a holder *g* and is secured therein by means of a thumb-screw *g'*. The holder *g* is formed upon or secured to a cross-piece *g''*, to one end of which is secured a depending guide-rod *g'''*, and the post *c* is made hollow to receive within it said guide-rod *g'''*, which slides up and down telescopically. The upper end of said cross-piece *g''* has secured to it one end of a threaded rod *g'''*, the threads formed thereon having one half the pitch of the threads formed upon the exterior of the screw-shaft *d*. The screw-shaft *d* is made hollow and interiorly screw-threaded to receive within it said threaded rod *g'''*, which is moved up and down by the turning of said hollow screw-shaft *d*. It will thus be seen that when the screw-shaft *d* is rotated, either by the rotation of the shaft *D* or otherwise, the upper carbon *B* will be fed downward at half the rate of speed at which the lower carbon is fed upward, which relation is in proportion to the consumption of the respective carbons and results in maintaining the arc in a fixed position. A short shaft *h* is journaled in the base *C*, which has fixed thereon a pinion *h'*, that meshes with a pinion *h''*, fixed to the screw-shaft *d*, and said short shaft *h* projects down through the base *C*, and its lower projecting end is squared to receive a wrench or other implement by means of which to revolve the shaft *d* by hand, and so facilitate the adjustment or replenishing of the carbons *A* and *B*. The supporting-rods *i i'* are secured at their lower ends to a disk *i''*, of wood or other suitable non-conducting material, and said disk is hollowed out upon its upper face to receive

the base *C*. The upper extremities of the supporting-rods *i i'* are united by a cross-piece *i''*, of wood or other non-conducting material, and to said cross-piece an eye *i'''* is secured by means of which the lamp may be suspended.

Upon the disk *b* is mounted an arc forming or striking magnet *j*, the armature *j'* of which is attached to a lever *j''*, pivoted at one end to a post or upright support *j'''*, the free end of said lever being forked and disposed to rest upon the holder *a*. Circuit contact-springs *k k'* are secured to a block *k''* of insulating material secured to the disk *b*. The contact-springs *k k'* are connected by a wire *k''* with the coils of the arc-forming magnet *j* and their free ends straddle and slide along upon the rod *i*. To the upper end of the rod *i'* one wire of the main circuit is attached, the other wire of said circuit being attached to the upper end of the rod *i*.

To the lower end of the shank *a''* of the carbon-holder *a* is attached a wire *k'''*, which connects with the coils of the arc-forming magnet *j*.

The spring *a'''* tends to hold the lower carbon up against and in contact with the upper carbon until the arc-forming magnet is energized, when its armature will be drawn downward, carrying with it the lower carbon and moving said lower carbon a distance sufficient to produce and establish the arc properly between the two carbons.

The motor which serves as the actuator for the feeding mechanism comprises a field-magnet *G* and a rotary armature *D'*, and said field-magnet *G* is included in the main circuit, in series with the carbons, and the rotary armature is included in a branch circuit, and said rotary armature is secured to or mounted upon the shaft *D*, to which the worm is secured. *l l'* are the two members of a circuit-closer which is provided for said branch circuit containing the rotary armature and which normally holds open the branch circuit and when operated closes it, and when said branch circuit is open said rotary armature is at rest, but when said branch circuit is closed said rotary armature revolves.

It is desired to operate the circuit-closer by a device responsive to variations in the current produced by changes in the resistance of the arc, and as a device of this character I provide the field-magnet *G* of the motor with a supplemental armature *l''*, which is pivoted at 50, and which is connected by a link 51 with one of the members of said circuit-closer. The field-magnet *G* is included in the main circuit in series with the carbons, and the coils of said field-magnet are connected by means of a wire *l''* with a bracket *m*, which is in contact with the base *C*. The wire *l''* is also connected with the commutator-brush *n* of the motor. The opposite end of the coil of the field-magnet *G* is connected by a wire *l'''* to a binding-post *o*, which is sup-

ported upon the frame of the field-magnet G and insulated therefrom. The post o is also connected by a wire o' with the fixed member l' of the circuit-closer, and said wire o' is part 5 of the branch circuit, in which is included the rotary armature D' of the motor. A wire o² connects the movable member l of the circuit-closer with the commutator-brush n' of the motor, and the said wire o² also forms a part 10 of the branch circuit within which the rotary armature of the motor is located. A wire p connects the post o with the rod i.

The circuit of the lamp is as follows: Starting at the connection at the upper end of the 15 rod i the current passes down through the rod i' to the brushes k k', through the wire k² to the arc-forming magnet, and thence through the wire k³ to the lower and upper carbons, and down the rods g³ and g⁴ and shaft d and 20 rod c into the base C, and from the base C through the wire l⁴ to the field-magnet G, thence to the post o, and then by wire p to the rod i and to the line.

The passing of the current through the 25 field-magnet G causes the same to magnetically attract and move the supplemental armature l³ in a direction to move the member l of the branch circuit-closer, so as to open the branch circuit, and during the operation of 30 the lamp this switch or circuit-closer is held normally open until the resistance due to the consumption of the carbons and strengthening of the arc is such that the strength of the field-magnet is reduced to such an extent that the member l of the circuit-closer, which 35 serves as a retractile spring for the supplemental armature, will overcome the strength of the field-magnet and will cause said armature l³ to retract and close the branch circuit. 40 The rotary armature of the motor will then be caused to rotate, and through the medium of the worm f and worm-gear e the shaft d will be revolved and the disk b, carrying the lower carbon, will be fed upwardly, while the upper carbon will be fed downwardly simultaneously at 45 half the rate of speed at which the lower carbon is fed upwardly. When the resistance is reduced at the arc, which will occur when the carbons approach each other, the strength of 50 the field-magnet G will increase to a sufficient extent to attract the armature l³, open the branch circuit, and thus stop rotation of the armature, and consequently the feeding of the carbons. This condition exists until the 55 resistance is again increased, due to the consumption of the carbons and lengthening of the arc, when the operation will be repeated.

Upon the rods i and i' is mounted a reflector-disk r, which is placed in the inverted 60 position shown, and supported between nuts s, fitted to the threaded portions of the rods i and i'. The bottom of the disk r is arranged so as to come below the arc and to reflect the rays of light therefrom upwardly 65 against a ceiling from which the lamp may be

suspended, and the light is reflected downwardly from the ceiling and diffused uniformly about a room or the like, so as to give the best illuminating effects. The disk r is formed with a centrally-located opening r' 70 through the bottom thereof, which is lined with a bushing r² of asbestos or other suitable heat and electrical insulating material, through which the lower carbon projects to the upper side of the disk r. Openings r³ r³ 75 are also provided, which permit of the passage freely therethrough of the shaft d and post c.

It will be seen that the field-magnet G not only serves its purpose as the field-magnet of the motor, but also acts as a relay to control 80 the movements of the supplemental armature l³, movement of which to and from the field-magnet opens and closes the circuit-closer.

The rotary armature of the motor is in multiple with the field-magnet, and the voltage it will receive will depend upon the length of the winding upon the field and upon the amount of current passing in that winding. 85

I claim—

1. In an electric-arc lamp, an actuator for the carbon-feeding mechanism consisting of a motor comprising a field-magnet in series with the carbons having two pairs of poles, a rotary armature between the poles of one 95 pair, a normally open branch circuit therefor, a circuit-closer for said branch circuit, a supplemental armature for operating said circuit-closer, located opposite the poles of the other pair responsive to variations produced 100 by the varying resistance of the arc, substantially as described.

2. In an electric-arc lamp, feeding mechanism for the carbons comprising a feeding-screw for each carbon, one of which is made 105 hollow and internally screw-threaded to receive the other, means for turning said hollow screw-shaft by hand, and an actuator consisting of a motor comprising a field-magnet, and a rotary armature, the latter being operatively connected with said hollow screw-shaft, substantially as described.

3. In an electric-arc lamp, the combination with actuating mechanism, of feeding mechanism for the carbons comprising a hollow 115 shaft externally and internally screw-threaded, the internal threads having one-half the pitch of the external threads, said shaft receiving upon it the lower-carbon support, and receiving within it a screw-threaded rod which 120 is connected with the upper-carbon support, substantially as described.

In testimony whereof I have signed my name to this specification in the presence of two subscribing witnesses.

CLARENCE C. STIRLING.
